WITNESS:

J. L. Brockman

INVENTOR
Loris Steinberger
BY
Conrad C. Billings
ATTORNEY

UNITED STATES PATENT OFFICE.

LOUIS STEINBERGER, OF BROOKLYN, NEW YORK.

INSULATOR.

Application filed November 23, 1917. Serial No. 203,478.

To all whom it may concern:

Be it known that I, LOUIS STEINBERGER, a citizen of the United States, and a resident of Brooklyn, county of Kings, city and State 5 of New York, have invented certain new and useful Improvements in Insulators, of which the following is a specification.

My invention relates to suspension or strain type of insulators for high tension 10 lines arranged in groups of two or more unit insulators per group, connected in series with each other, each unit insulator of a group having a different electro-static capacity from the other unit or units of the 15 group, whereby a more uniform distribution of the electrical tension or stress between the charged line and the support or tower for the group of insulators is secured.

One of the objects of my invention is to so 20 construct the individual unit insulators of a group and to so arrange these unit insulators in series that a group of individual units will provide an insulator which will have ability to withstand exceedingly high 25 voltages.

Another object is to so construct the unit insulators of the group and to so grade them with respect to their electro-static capacities as to equalize the voltage distribution.

30 Another object is to save material and cost of construction and also to lessen the weight without decreasing the efficiency.

Other objects will hereinafter appear from the subjoined specification and claims.

35 Referring to the drawings:

The figure is a vertical section of a group of insulators embodying my invention, the support being illustrated also in section and the line wire and clamp for securing the 40 same to the lower insulator being shown in elevation.

I have illustrated a type of any preferred form of disc insulator and of interlocking strain members embedded therein, which 45 strain members are provided with means well known in the art and which have been disclosed by me in my prior patents for securing the one to the other, the construction of which is only necessary to describe 50 generally herein.

I provide a construction and arrangement of grouped unit insulators whereby the electrostatic capacities of the individual insulators of a group differ from each other so as 55 to secure a uniform distribution of the electrical stresses or strains to which the unit in-

sulators of a group are subjected. The electrostatic capacities of the individual insulators of a group are made to differ from each other by using electrical conducting 60 rings or skirts in connection therewith of varying surface areas as more fully described below. The largest ring or skirt, or one having the largest surface area, is used with the insulator of largest diameter 65 which is placed next to the line wire, and the smallest ring or skirt is used with the insulator having the least diameter placed next to the support, and the intermediate insulators with rings are graded accordingly 70 thereby producing a gradation in electrostatic capacities of the individual insulators of a group from the one of largest diameter to that of the smallest diameter.

In a group of three insulators, such as 75 shown in the drawing, the insulator nearest the line wire has the greatest diameter and the greatest electrostatic capacity. The insulator just above the lowest insulator has a diameter and also an electro-static capacity greater respectively than the diameter and the electro-static capacity of the insulator just above it, but less in each respect than those of the next lower insulator.

80 My invention, however, is not limited to 85 a construction in which the insulators comprising the group have graded diameters only, for it may be applied to a series of unit insulators all of which have the same diameter. It is, however, necessary that the 90 unit insulators have graded electro-static capacities, that is, the rings are graded with respect to their surface areas from line to support as above described.

I have used the word "above" in describing the invention when applied to a group of suspension insulators, as illustrated, but it is to be understood that the invention is applicable to a group of insulators when used as strain insulators, in which case each 100 insulator may be situated in a horizontal relation to each other.

Referring to the figure of the drawing, 10 is a disc insulator and 11 and 12 the respective interlocking mechanical strain members, 105 which are embedded in the body of the disc insulators, the strain members 12 being provided with screwthreaded means, as shown at 13, for removably securing the parts of the strain member together, all of which is 110 now well known in this art.

S is a support for the series of insulators

from which they are suspended, or to which they are secured by any suitable holding means as illustrated at 14. 15 is a line wire and 15' a conventional clamp by means of which the wire is secured to the lowermost strain member.

In constructing my invention I partially embed a metallic ring in the periphery of each of the disc insulators during the molding thereof.

By embedding rings of different surface areas in the different disc insulators their electrostatic capacities can be made to differ in the desired manner in accordance with the 15 well-known fact that the surface area of a metallic element is a factor which governs its electro-static capacity.

When the insulators are of disc shape these metallic elements are ring shaped. 20 The form of metal ring which is embedded in the peripheral edge of each of the insulators, which I have found to be preferable for use with suspension insulators, is that illustrated in the drawing and designated 25 16, 16' and 16''. The metal rings 16, 16' and 16'' may be defined as "skirt" shaped rings and each is substantially rectangular in cross section, the inner edge of which should preferably be corrugated or roughened, as at 20, so as to provide an effective 30 holding surface for securing it to the insulating material. As shown, the peripheral ring 16'' of the lower insulator is of greater surface area than that of the peripheral ring 16' of the insulator just above it, and the peripheral ring 16' is of greater surface area than that of the peripheral ring 16 secured to the insulator immediately above it; so that the rings are graded with respect 35 to their surface areas and by this construction they are graded with respect to their 40 electro-static capacities.

While in the drawing the unit insulators as well as the metallic rings are of different 45 diameters, it is to be understood that my invention is neither limited to the construction of insulators per se, nor of the metallic rings per se, but pertains to the particular grouping and grading in the respective unit 50 insulators provided with metallic rings constituting the group, as set forth herein.

When insulators are used which are provided with metallic rings as described and shown, the arcing will take place from the 55 line to the ring embedded in the insulator nearest the line, and from that ring to the ring embedded in the next unit, and from there to the next unit above, and so on throughout the units composing the group.

60 By the arrangement described the metallic rings, together with the dielectric material consisting largely of air and partly of the insulating discs constitute a number of condensers of different electrostatic capacities 65 connected in series, the one of greatest elec-

trostatic capacity being nearest the line. The electrostatic capacity to which reference is made in this connection is the electrostatic capacity of each insulating unit between the strain members 11 and 13 due primarily to the capacity of the rings 16, 16', and 16'', 70 when referred to a common ground or to zero potential. Since the potential across a condenser is directly proportional to its charge and inversely proportional to its 75 capacity, it is desirable to have the capacities of the condensers nearer the line correspondingly larger than the capacities of those more remotely situated in order for the potentials across them to be more nearly 80 uniformly distributed so as to avoid throwing an excessive electrical stress on any single unit of the group.

In addition to the electrical value of the insulator provided with the projecting 85 peripheral metallic rings, these rings also have a mechanical function in that they will prevent the possible chipping of the peripheral edge of the insulator because of possible rough handling during shipment or transportation of the insulators. This function is, of course, incidental and in addition to the main purpose of the invention.

Any suitable insulating material may be used in making the structure described, but 95 I prefer to use that particular insulating material known in the art as "electrose."

As changes of construction could be made within the scope of my invention, it is intended that all matter contained in the 100 above description or shown in the accompanying drawings shall be interpreted as illustrative and not in a limiting sense.

Having now described my invention, what I claim as new and desire to secure by Letters Patent is:

1. In a device of the class described, a series of unit insulators each unit provided with strain members, said units being connected together to form a group, each unit 110 having a single auxiliary metallic element connected thereto and insulated from the strain members, said units being arranged in graded relation with respect to the electrostatic capacities of the auxiliary metallic 115 elements, the least being nearest ground and the greatest nearest to the line, the remainder being graded accordingly.

2. In a device of the class described, a series of disc insulators each disc being provided with strain members said insulators being connected together by means of the strain members to form a group, each disc having a single auxiliary metallic element embedded in its periphery, and insulated 120 from the strain members and extending beyond said disc in a radial direction, said discs being arranged in graded relation with respect to the electrostatic capacities of the auxiliary metallic elements, the least nearest 125 130

ground and the greatest nearest to the line.

3. In a device of the class described, a series of disc insulators each of which is provided with strain members said insulators being connected together by means of said strain members to form a group, each disc having a single auxiliary annular metallic element connected thereto and insulated from the strain members, said disc insulators being arranged in graded relation with respect to the electrostatic capacities of the auxiliary annular metallic elements, the greater being next to the line and the lesser next to ground.

15 4. In a device of the class described, a group of unit insulators each unit being provided with strain members, and each unit having a metallic ring embedded in its periphery and insulated from the strain members, said rings being graded with respect to the surface areas of said rings, the ring of least surface area being next to ground, and the ring of greatest surface area being next to the line, the 20 intermediate rings being graded accordingly.

5. In a device of the class described, a group of disc insulators each disc being provided with strain members and a peripheral ring of metal insulated therefrom, said rings being increasingly graded with respect to their electrostatic capacities from ground to line.

6. In a device of the class described, a group of disc insulators, each disc being provided with strain members and a peripheral metal element molded therein and insulated from the said strain members, said insulators being increasingly graded with respect 40 to the electrostatic capacities of the peripheral metallic elements from ground to line.

7. In a device of the class described, a group of unit insulators, each unit of the group having strain members and a ring of metal partially embedded in its periphery and insulated from the said strain members, the ring of metal in the unit next to the line having a greater surface area than any one of the other rings.

50 8. In a device of the class described, a group of unit insulators, each unit of the group having strain members and a ring of metal partially embedded in its periphery and insulated from the said strain members, the ring of metal in the unit next to the line

being of such shape and size as to have a larger electrostatic capacity than any of the other units of the group.

9. In a device of the kind described, a group of insulators consisting of two or more unit insulators secured together, each of said unit insulators having strain members and a hood-shaped projecting metallic ring molded in its periphery and insulated from the strain members, the rings being graded in electrostatic capacity, the least next to ground and the greatest next to the line.

10. In a device of the class described, a group of connected insulators each insulator of the group being provided with connecting means, the insulator at one end of the group being secured to a support, the insulator at the other end being secured to a line, the insulator secured to the support having a metal ring of a certain surface area partially embedded in its periphery, the insulator next thereto having a metal ring of larger surface area partially embedded in its periphery, and so on through the group, the insulator that is secured to the line having a metallic peripheral ring of the maximum surface area of any ring of the group each of the rings being insulated from the connecting means of its insulator.

11. In a device of the class described, a group of connected insulators each insulator of the group having connecting means secured thereto, the insulator at one end of the group being secured to a support, the insulator at the other end being secured to a line, the insulator secured to the support having a metal ring of a certain electrostatic capacity, partially embedded in its periphery, the insulator next thereto having a metal ring of larger electrostatic capacity partially embedded in its periphery, and so on through the group, the insulator that is secured to the line having a metallic peripheral ring of the maximum electrostatic capacity of any ring of the group, each of the rings being insulated from the connecting means of its insulator.

Signed at the borough of Manhattan, city, county and State of New York, this 15th day of November, 1917.

LOUIS STEINBERGER.
